UNITED STATES PATENT OFFICE.

LUTHER L. DUKE, OF EDISON, GEORGIA, ASSIGNOR OF ONE-HALF TO B. H. JOHNSON, OF DICKEY, GEORGIA.

PEANUT-HULLER.

1,335,669.

Specification of Letters Patent. Patented Mar. 30, 1920.

Application filed February 14, 1918. Serial No. 217,237.

To all whom it may concern:

Be it known that I, LUTHER L. DUKE, a citizen of the United States, residing at Edison, in the county of Calhoun and State of Georgia, have invented certain new and useful Improvements in Peanut-Hullers, of which the following is a specification, reference being had therein to the accompanying drawing.

This invention relates broadly to improvements in that class of inventions known as separators and more particularly has reference to a peanut huller.

As the principal aim and object this invention resides in the provision of a huller for shelling peanuts and the like so as to separate the kernels from the shells and is capable of adjustment for effectively acting on various sizes of peanuts.

It is an equally important object of this invention to provide a peanut huller wherein peanuts are fed thereinto simultaneously with the actuation of the machine in order that peanuts may be continuously separated when the machine is in operation.

More particularly this invention embraces the provision of a peanut huller embodying fanning means operating simultaneously with the hulling means for separating the shell from the kernel so that both the shells and the kernels may be consequently deposited in separate receptacles.

It is a more specific object of this invention to provide a peanut huller of such a character that all of the parts are compactly and operatively arranged and designed to operate simultaneously with each other so as to insure an effective hulling and separating of the peanuts from their shells.

Among the other aims and objects of this invention may be recited the provision of a device of the character described with a view to compactness, and in which the parts are few, the construction simple, the cost of production low and the efficiency high.

Other improvements and novel details in the construction and arrangement of the various parts of the apparatus will be brought out more in detail in the description to follow, which for a clear understanding of the invention should be considered in connection with the accompanying drawings forming a part hereof, and wherein is disclosed for the purpose of illustration a convenient and satisfactory embodiment of the invention. It is to be noted in this connection that minor

changes in the construction and arrangement of parts may be made without departing from the principle of operation of the various parts.

The invention is clearly illustrated in the accompanying drawings, in which:

Figure 1 is a side elevation of the invention;

Fig. 2 is a transverse section thereof; 65

Fig. 3 is a longitudinal section;

Fig. 4 is an end elevation;

Fig. 5 is a detail of the concave.

Similar characters of reference are employed in all of the above described views, 70 to indicate corresponding parts.

Referring now, more particularly, to the accompanying drawings, there is provided improved supporting means in the present instance consisting of a rectangular open frame and which includes a plurality of standards 1 connected at their upper ends by longitudinal beams 2 and transverse beams 3 and also connected intermediate their ends with other longitudinal beams 4 80 and transverse beams 5.

The feeding means consists of a feeding hopper 6 the upper end of which is pivotally connected to supporting rods 7 carried by the frame while the hopper is inclined and has its lower end resting on a shaking block 8 square in cross section and carried by a shaft 9 the respective ends of which are journaled in bearing brackets 10 carried by the upper longitudinal beams adjacent one end of the frame.

With a view toward providing improved hulling means a concave indicated in its entirety by the numeral 11 is employed and consists of a pair of disk castings 12 rigidly secured in the upper longitudinal beams 2 beneath the feeding hopper 6. Each of the castings is provided with a central opening 13 while the lower portion thereof is provided with a series of radial slots 14 100 for a purpose that will presently appear. A metallic band 15 is shrunk about the periphery of each casting. A plurality of grate bars 16 are now provided and each one is arranged transversely between the two castings the respective ends thereof being slidably positioned in opposed slots 14. The improved means for adjusting these bars consists in a plurality of set screws 17 the threaded shanks 18 of which are adjustably mounted in correspondingly threaded openings 19 in the bands or rims 15 while

the inner ends are swivelingly connected to the sides of the bars 16. Of course by adjusting the heads 20 of the set screws, the bars may be adjusted relative to the center 5 of the disks 12. Filler blocks 21 may be inserted in the inner ends of the slots and prevent the passage of hulled peanuts therethrough.

A transverse shaft 22 has its respective 10 ends journaled in the openings 13 while a hulling cylinder indicated in its entirety by the numeral 23 is rigidly mounted on this shaft and rotates above and within the concave 11. This cylinder consists of a solid 15 body 24 on the periphery of which is mounted a plurality of suitably spaced slats or bars 25 which coöperate with the bars 16 in hulling peanuts. The adjustability of the bars 16 of course permits of various size 20 peanuts being readily accommodated in the hulling means so that they may be effectively hulled without being injured. An inclined chute 26 has its upper end suitably supported by the bars 2 beneath the hulling 25 means and terminates a short distance above the longitudinal beams 4.

As intimated, suitable means have been provided for separating the hulls from the kernels. In reducing this feature of the invention to practice a fan casing 27 is mounted 30 between the opposed standards 1 while an outlet pipe 28 projects therefrom and terminates immediately beneath the chute 26. The fan consists of a shaft 29 journaled 35 transversely in the casing 27 and on which is rigidly mounted a hub upon the periphery of which extend radial fan plates 31. The rotation of the shaft of course forces air through the pipe 28, the air being drawn 40 in through the center outlet 30.

Coöoperating with the hulling and fanning means is a conveying means which consists of a chute 32 mounted in the supporting frame and inclined downwardly toward the 45 chute 26 and the outer end of the pipe 28 terminating in a suitable point beneath the pipe 28. The purpose of this conveying chute is to provide means for the separation of the kernels and shells, the former moving down the chute while the latter acted upon by the air through the pipe 28 are forced upwardly and out through the upper end of the chute. Suitable means of course may 50 be provided to receive the shells.

For the purpose of actuating all the parts of the machine simultaneously with each other a drive pulley 35 is carried by one projecting end of the shaft 22 and has a belt 34 trained thereabout which is also operatively connected with a suitable source 55 of power not shown. Another pulley wheel 33 is carried by the shaft while a belt 36 is trained thereabout and is also trained about a small pulley wheel 37 carried by the fan 60 shaft 29. In order to actuate the hopper

so as to deposit peanuts in the hulling means a sprocket wheel 38 is connected to the opposite end of the shaft 22 while a sprocket chain 39 is trained thereabout and is also trained about a sprocket wheel 40 on the 7 shaft 9.

The mode of operation of the present invention may be reviewed as follows:

Assuming that the parts have been assembled in the manner described rotary motion is imparted to the main shaft 22 by the belt 34 which operates about the drive pulley 35. The cylinder 23 of course rotates with the shaft 22 while the slats or bars 25 coöperate with the grate bars 16 in producing a crushing action on the peanut hulls which are deposited by the feeding means. During this actuation owing to the sprocket wheels 38 and 40 on the shafts 22 and 9 and the chain 39 which operates thereabout, the block 8 will be rotated to raise and lower the lower end of the hopper 6 or in effect shift the hopper so that the peanuts will be deposited into the hulling means. The fan also actuates simultaneously with the hulling and feeding means so that when the shells and kernels slide down the chute 26 the air which is forced through the pipe 28 will move the shells up the chute so that they may be subsequently properly handled 95 in a convenient manner while the kernels will not be subjected to the action of the air but will continue down and fall from the chute 32 and be subsequently deposited in a suitable receptacle not shown beneath the 100 chute 32.

Having thus fully described this invention, what is claimed as new and desired to be secured by Letters Patent, is:

A peanut huller embodying a supporting 105 frame, a concave mounted therein and including a pair of spaced disk-like castings, the said castings being formed with a plurality of uniformly spaced radial slots opening on their peripheries, the disks being 110 vertically disposed and the slots being confined to the under edges thereof, rings surrounding the disks and closing the ends of said slots, transversely disposed bars mounted in opposite slots of the two 115 disks adjusting screws passing threadingly through said rings and being radially disposed in said slots and having swivel connections at their inner ends with said bars whereby the bars may be adjusted toward 120 and away from the center of said disks so that filler blocks may be inserted in the bottom of said slots for the bars to bear against, and a rotatably mounted cylinder disposed between said disks and provided with means 125 for coöperation with said bars to effect a crushing operation as the cylinder is rotated.

In testimony whereof I affix my signature.

L. L. DUKE.
